(57) CLAIM

The ornamental design for a bench as shown and described.

DESCRIPTION

FIG. 1 is a top perspective view of a bench;

FIG. 2 is a bottom perspective view of the bench shown in FIG. 1;

FIG. 3 is a left-side elevational view of the bench shown in FIG. 1;

FIG. 4 is a front elevational view thereof;

FIG. 5 is a rear elevational view thereof;

FIG. 6 is a top plan view thereof; and,

FIG. 7 is a bottom plan view thereof.

The broken line portion of the figure drawings are included to show portions of the bench that form no part of the claimed design. The dash-dot-dash broken lines shown in FIGS. 2 and 7 are for the purpose of depicting boundary line bottom portions of the bench and form no part of the claimed design.

1 Claim, 7 Drawing Sheets
